UNITED STATES PATENT OFFICE

2,465,632

TUMBLE BARREL

Paul P. Burns, Philadelphia, Pa.

Application April 8, 1947, Serial No. 740,138

1 Claim. (Cl. 51—164)

1

The object of the invention is to provide improvements in tumble barrels broadly, but more particularly in details of construction and operation, whereby during operation of the tumble barrel the relatively fine burrs, grit and the like separated from the articles being "tumbled" are continuously being separated from such articles.

Another object is to provide the combination of a tumble barrel having apertured peripheral walls through which the finer particles of grit, burrs and the like can pass from within the barrel as it rotates, together with means to vary at will the aggregate cross sectional areas of the combined apertures.

A further object is to provide in such a device a drawer or movable bin into which the undesirable refuse particles are caught as they gravitate from within the barrel, and by means of which they can be removed at will without necessitating that they be separated from the articles being tumbled after the tumbling and cleaning operation is completed.

Still another object is to provide a device of this character in which two or more reciprocatable drawers are located beneath the barrel, the one or more drawers above the lowermost drawer being provided with screen or apertured bottoms, whereby selected sizes of particles can be automatically separated from one another, as they drop from within the barrel, the finer particles proceeding to the lowermost drawer while the larger particles are arrested by and remain in an upper drawer, and the sizes of the openings in the bottom of an upper drawer being also capable of adjustment if desired.

With this brief statement of the objects, the invention comprises further details of construction and operation, which are hereinafter fully brought out in the following description, when read in conjunction with the accompanying drawings, in which Fig. 1 is a side elevation of a complete tumble barrel comprising one embodiment of the invention; Fig. 2 is a front elevation of the same; Fig. 3 is a perspective view of the tumble barrel or cylinder per se; Fig. 4 is an enlarged fragmentary plan view of a portion of one apertured side of the tumble barrel with a corresponding portion of one of the aperture controlling slides mounted thereon; Fig. 5 is a section of one of said apertured sides with its slide in fully opened position along a line indicated by the line 5—5 of Fig. 4; Fig. 6 is a similar section but showing the slide adjusted so as to decrease the effective size of the openings in the barrel's side wall; Fig. 7 is an enlarged side elevation similar

2

to that shown in Fig. 1 but with a portion of the end wall broken away to disclose the barrel, sloping wall and trays within the outer casing; and Fig. 8 is a front elevation similar to Fig. 2 but showing a portion of the front broken away for the same purpose.

Referring to the drawings, one embodiment of the invention is shown as comprising an outer casing which is composed of end walls 1, a rear wall 10 2, a bottom 3, a restricted top wall 4, a diagonally extending upper wall 5 that connects the upper edge of the rear wall 2 with the rear edge of the top wall 4, a closure 6 that is hinged at 7 of the forward edge of said top wall, and a pair of outwardly opening doors 8 that together form when closed a front wall, and which are hingedly mounted at 9 upon the forward edges of said side walls, and which may be provided with manually engageable handles 10. Said closure 6 may be provided with a suitable handle 11, and while it is normally in lowered or closed position, it may be swung upwardly and reversely until it rests upon said top wall, thereby providing an opening and permitting access to the barrel within.

15 The tumble barrel per se is composed of preferably polygonally shaped end walls 12 to which are secured by any suitable means 13 oppositely extending trunnions 14, said trunnions passing outwardly through the end walls 1 of the casing 20 through suitable bushings 15. To one of these trunnions is secured a pulley 16, which broadly represents any available and suitable means for rotating said barrel at the desired speed.

25 One or more of the plane walls or sides 17 of 35 said barrel may be imperforate if preferred, while one of them is normally closed by means of a removable panel 18 having a handle 19, and which when opposite the opening of the casing and the closure 6 lifted permits articles to be treated to 40 be placed in said barrel, after which the closure 18 is replaced and the casing closure 6 returned to closed position. The barrel closure panel 18 may be removably secured in operative position by any suitable means, such for instance as the 45 thumb nuts or screws 20.

Each of the barrel's peripheral walls or sides 21 between the imperforate side or sides 17 and the closure wall 18 is provided with preferably though not necessarily regularly spaced apertures 50 22 of the same or different diameters or other cross sectional areas. Slidably mounted to reciprocate upon each of these apertured sides is a plate 23, having apertures 24 that in number, size and arrangement substantially correspond 55 with the same characteristics of the apertures 22

in the sides 21. Each slide is restrained to move in a rectilinear path by pin-and-slot or other suitable means 25, while each slide is secured in any desired position by means of thumb screws 26 or the like, so that by adjusting and securing each slide in a given position, the desired effective area of the apertures 22 in the barrel sides is obtained and maintained.

In the lower rear part of the interior of said casing is positioned a slanting wall 27 that serves to guide dust and particles falling from the tumble barrel towards the one or more receiving trays that are positioned in the lower portion of said casing adjacent to or actually resting upon the bottom wall 3. These trays may be of any desired number, but for purposes of illustration two of them are shown. The lower tray 28 may slide upon the bottom 3 or may be slightly spaced above the same, and is removable when the frontal doors 8 are opened. The upper tray 29 is likewise movable independently of said lower tray upon any suitable means such for example as the guides 30 carried by the side walls 4 of said casing. And said trays receive particles from within the barrel, as they drop directly thereinto or first drop upon the rear slanting wall 27 and thence fall into the trays.

One tray alone is used when no selection is desired between the sizes of the particles falling from the barrel as it rotates. However, if selection of such particles as to size is desired, two or more such trays are used. In this case, the upper tray is provided with an apertured bottom wall 31, or a bottom may comprise a wire or other form of mesh having apertures of predetermined areas, which will in most if not every case be less than that of the apertures in the barrel sides when restricted by the positions of the slides 23. For example, as articles are being treated during rotation of the barrel, particles of various sizes fall therefrom, due to the abrasion of one such article against the irregular edges and other portions of the other articles, and the small burrs, flanges and the like, especially those incident to the formation of molded, cast, punched and/or stamped articles, are removed and fall through the apertures 22 in the barrel sides.

If only large articles are being treated, the slides may be in fully opened position. But if small articles, such for instance as small sizes of screws, bolts, nuts and the like, are being treated and these articles are of such size that they would otherwise pass through the barrel apertures, the latter are suitably restricted by adjustment of said plates 24. Thereafter, if the particles falling through said barrel apertures are to be classified, as for example into dust and larger sizes, two or more superimposed trays are used, in which case the dust falls through into the lowermost tray, while the next larger size of particles are arrested in the tray next thereabove, since they cannot pass through the apertures of the mesh or apertured bottom of the upper tray 29. Also, if desired the apertures in said upper tray may be regulated in any suitable manner, as for example by means of plates such as are used to control the areas of the apertures in the barrel sides hereinbefore described.

In any case, after a batch of articles has been treated in the barrel, and the refuse removed by means of the one or more trays, the closure 6 of the barrel may be removed, and the barrel turned until the treated articles fall into a tray therebeneath, by means of which the treated articles may then be removed, and the barrel re-

turned to receiving position with its still open side in line with the opening made available by lifting of the closure 6, and fresh articles poured or dumped into the barrel, after which the barrel closure 18 is replaced, the closure 8 likewise replaced, the front doors 8 closed, and the barrel again started to rotate in the usual manner.

If desired, the unusually fine dust produced in some tumble barrel operations may be drawn off by a suction fan or blower 32 connected to an exhaust pipe 33 leading from any desired part of the casing, in which case a screened entrance for fresh air may be provided in some part of the casing spaced therefrom, and the finest particles falling into the lower tray are previously freed from such dust.

In addition to the new tumble barrel comprising an improved machine as such, it makes possible the highly efficient functioning of a new method or principle in the operation of apparatus of this type. For example, many articles whether of plastic or of metallic nature, it has been found advantageous to treat in steps, beginning with the tumbling of the articles themselves alone in the barrel with all discharge holes closed for a period of about a half-hour more or less, depending upon the type, shape and material of which the articles are formed. There are then placed in the barrel with said articles one or more sizes of treating devices, such as one or more sizes of balls, after which the tumbling is continued as the balls, usually of small size, enter the deeper and narrower irregularities and recesses of the articles, while larger balls if present treat the outer surfaces and edges. When the articles have been sufficiently treated, the barrel is stopped and the gratings opened sufficiently to pass the waste alone, and then opened wider to pass the balls of a given maximum size, which fall into a single tray therebeneath, the waste being disposed of before the balls are released into said tray. However, if two or more sizes of balls are used in treating the articles, after the latter have first been tumbled upon and among themselves without the addition of treating devices; upon stopping the barrel the gratings are opened sufficiently to pass the smallest size of balls during a few revolutions of the barrel in addition to or subsequent to passage of the waste, after which the gratings are opened farther and balls of a larger size permitted to pass therethrough. Also, with either a single size or a multiplicity of sizes of balls being used, two (or more) trays may be employed, in which case the waste dust and grit removed from the treated articles falls with the balls (or other form of treating device) through the barrel's apertures, but the balls are arrested in the uppermost tray for reuse, while the dust and grit passes through the mesh or apertures in such upper tray into the lower tray, so that it can be removed without the chance of loss of balls. Also, if three or even more trays are used with different graded sizes of apertures in their bottoms, the entire collection of waste and treating devices may be released simultaneously and separated as they fall from tray to tray. Thus, there are numerous ways and combinations in which the details and functions of the several parts of the device may be operated in carrying out the improved method of tumbling and subsequent separation of treating devices and waste from one another and in grading either or both of said devices and waste as desired.

Having thus described my invention, what I

claim and desire to protect by Letters Patent of the United States is:

A tumble barrel, comprising a casing which in turn comprises substantially vertical bottom, front, rear and side walls topped by a polygonally shaped covering wall, said front wall being composed of hinged doors and one of the sections of said covering wall being a hinged closure, a plurality of independently slidable drawers in the lower portion of said casing, the upper drawer having an apertured bottom and the lowermost drawer having an imperforate bottom, a shaft extending through and rotatable with respect to said end walls, a polygonally shaped tumble barrel mounted to rotate upon the axis of said shaft, one of the flat sections of said tumble barrel being removable for insertion and withdrawal of articles, others of said flat sections being provided with apertures, slidably mounted apertured gratings carried by said last-mentioned flat sections, means to secure said gratings in such positions as to predetermine the effective sizes of the apertures in the corresponding sides of the barrel, and means within said casing to deflect the fall

of particles from said barrel to the uppermost of said drawers.
